SUCTION CLEANER

William H. Kitto, Canton, Ohio, assignor to The
Hoover Company, North Canton, Ohio, a cor-
poration of Ohio

Application July 18, 1931, Serial No. 551,672

17 Claims. (Cl. 15—6)

The present invention relates to suction cleaners generally, and particularly to new and improved surface-agitating means for a suction cleaner. More specifically the invention comprises a new and novel combination of surface-beating and brushing means with pile-agitating means in a suction cleaner.

It has long been the practice of suction cleaner builders to incorporate surface-agitating means as the requirement of such means for complete cleaning was well recognized. In the earlier cleaners the surface-agitating means comprised rotary brushes which were generally positioned within the suction cleaner nozzle and driven through power-transmitting means from the motor which drove the suction-creating fan. In other types of cleaners a vertically or horizontally reciprocating beater or agitating member was positioned within the nozzle and driven by some suitable means. In its later development the modern suction cleaner was provided with a rotary positive beating agitator within its nozzle, that is, a rotary member provided with rigid surface-contacting members which function, in operation, to positively vibrate the surface covering undergoing cleaning to dislodge the embedded foreign matter therefrom. Brushes were usually provided in combination with the rotary rigid surface-contacting elements. It has been discovered in the laboratories that the agitation of the pile of the surface covering, even in the absence of surface covering vibration, in the sense of vibrating the entire body of the covering at the point of cleaning, is effective to dislodge embedded and impacted foreign material at the base of the pile. It has also been found that this pile agitation or vibration is particularly effective when it takes place at the exact point at which the cleaning air is effective. To accomplish this last result the nozzle lips of the cleaner have, in some cleaners, been positively actuated. In some embodiments the entire suction cleaner nozzle was actuated in order to accomplish this lip vibration while in the more preferred embodiments the lips were moved relative to the nozzle. In the present invention applicant has embodied, for the first time in a suction cleaner, rotary agitating means and positively-actuated nozzle lips and has provided new and novel means for the actuation of the lips to accomplish their surface-pile-deflecting and vibrating function.

It is an object of the present invention to provide a new and novel suction cleaner construction. It is another object to provide, in a suc-

tion cleaner, a new and novel combination of rotary agitating and gyratory agitating means. A further object is the provision, in a suction cleaner, of vibrating agitating means which are driven from the rotary agitator. A still further object is the provision, in a suction cleaner, of the combination of a rotary positive agitator and vibrating nozzle lips which are actuated by the rotary agitator. A further object is the provision in a suction cleaner, of a rotary agitator provided with eccentric means to positively actuate the movable nozzle lips construction. Still another object is the provision, in a suction cleaner, of an eccentrically mounted rotary agitator which is connected to and adapted to actuate movable agitating nozzle lips. These and other more specific objects will appear upon reading the following specification and claims and upon considering in connection therewith the annexed drawings to which they relate.

In the drawings in which preferred embodiments of the present invention are disclosed:

Fig. 1 is a side view of a modern suction cleaner embodying a preferred embodiment of the present invention with the end wall of the nozzle in section upon the line 1—1 of Figure 2;

Fig. 2 is a cross section through the cleaner nozzle upon the line 2—2 of Fig. 1;

Fig. 3 is a partial cross section upon the line 3—3 of Fig. 2;

Fig. 4 is a section upon the line 4—4 of Fig. 5;

Fig. 5 is a partial cross section upon the line 5—5 of Fig. 4;

Fig. 6 is a view in perspective of one end of the agitator-supporting frame and the nozzle-lip-supporting frame, the rotary agitator being removed from the construction;

Fig. 7 is a view of the spring detail embodied in the nozzle lip frame being a partial section taken upon the line 7—7 of Figure 4;

Fig. 8 is a partial section upon the line 8—8 of Fig. 4;

Fig. 9 is a section similar to Figure 5, being a transverse cross section through the cleaner nozzle, with the agitator embodied therein, of a second embodiment of the present invention, and being taken upon the line 9—9 of Fig. 10;

Fig. 10 is a section upon the line 10—10 of Fig. 9;

Fig. 11 is a section upon the line 11—11 of Fig. 9;

Fig. 12 is a view in perspective of the resilient supporting element for the agitator in the embodiment shown in Figs. 9 to 15 inclusive;

Fig. 13 is a view in perspective of the enclosing cup member for the element shown in Fig. 12;

Fig. 14 is a view in perspective of one end of the vibrating agitating elements and one of their supporting end members;

Fig. 15 is a side view of the rotary agitating agitator and the vibrating agitators removed as a unit from the supporting frame;

Fig. 16 is a side view of a different type of rotary agitator adapted to be embodied in the construction shown in Figs. 9 to 14 inclusive.

Referring again to the drawings, and Figures 1 to 8 in particular, a preferred embodiment of the present invention is disclosed in a modern 15 suction cleaner comprising a nozzle 1; a fan chamber 2, which is interiorly connected to said nozzle through the air passageway 3; and an exhaust outlet 4 to which is attached, by suitable means 5, the dust bag 6. A motor casing 7 is positioned immediately above the fan chamber 2 and houses a suitable driving motor, the shaft 8 of which extends downwardly through the fan chamber 2 where it carries the suction-creating fan 9. A belt-receiving pulley 10 is carried at 20 the lower end of the motor shaft 8. The cleaner is movably supported by means of front supporting wheels 11, 11 and rear supporting wheels 12, 12, there being means, indicated generally by the reference character 13, by which the nozzle 1 25 may be raised and lowered about the front supporting wheels 11 as an axis. As in the usual suction cleaner a pivoted handle 14 is provided through the use of which the operator can easily move the cleaner over the floor.

35 A rotary agitator, indicated generally by the reference character 15, is positioned within the nozzle 1 and comprises a cylindrical body 16 which carries upon its surface the rigid elongated beater elements 17, 17, which extend helically 40 from common end points, and the longitudinally extending brushes 18, 18, which are positioned below the surface of body 16 and extend thereabove at a height substantially equal to the height of the beater elements 17, 17. Spacer elements 19, 19 are positioned upon the surface of the body 16 between the beater elements 17, 17 and the brush element 18, 18 which function to prevent the undue displacement of the surface covering within the nozzle between the successive 45 contacts of the said beater elements and the said brush elements. Body 16 is rotatably mounted upon the stationary through-supporting shaft by means of bearings 21, 21 at the ends of the agitator. Each bearing comprises an inner race 50 55 22, which is seated upon the reduced end of the stationary shaft 20, and an outer race 23, which is seated in a suitable seat formed in the agitator end plate 24 of the body 16. Between the outer race 23 of the bearing and the enclosing seat in the agitator end plate is positioned a cup member 25 which is provided with an outwardly extended portion at the side of the bearings 21 which has a cylindrical seat 26 which is eccentric 60 with respect to the shaft 20 for a purpose which will soon be apparent. Each end of stationary shaft 20 is supported in a slot 27 in the adjacent end plate 28 of the agitator-supporting frame, the latter comprising the two end plates 28, 28, 65 each pivoted as at 29 to the nozzle of the cleaner, and the transversely-extending members 30 and 31 which extend across the nozzle between the end plates and contact the front and rear nozzle walls, respectively. To prevent the unintended 70 displacement of the agitator-supporting shaft 20 75

a pivoted locking plate 32 is provided on each end member 28 which is pivoted at 33 which, through being provided with a cam surface 34 and being pivoted under the force of a spring 35, cooperates with the slot 27 to maintain the shaft 5 in position.

Encircling the eccentric seat 26 on each cup member 25 carried by each end of the agitator is a bearing 36 the inner race 37 of which non-rotatably seats upon the portion 26 and the outer race 38 of which seats in an end member or plate 39 which is provided centrally, as is clearly seen in Figure 6, with a seat 40. Each end member 39 is formed of a lower portion 41 and an upper portion 42 which is pivoted at one side, by means of the pivot pin 43, to the lower portion 41. A spring 44 encircles the pivot pin 43 and serves to force the two portions together. At the rearward side of each end member 39, opposite the pin 43, is positioned a thumb lock spring 45 which is carried by the upper portion 42 and which is provided with a projecting portion 46 of which is adapted to seat within a suitable opening 47 formed in the side wall of the lower portion 41 and which in place functions to lock the two 25 portions together. Between the end members 39, 39, which are positioned at the opposite ends of the rotary agitator, extend the surface-contacting members or lips 48 and 49 respectively. These lip members are rigidly attached to the 30 lower portions 41, 41 of the end members 39, 39 and are sealed, throughout their entire length, to the adjacent members 30 and 31, respectively of the agitator-supporting frame by means of the rubberized fabric strips or seals 50 and 51 35 which are suitably connected therebetween, and which are sufficiently flexible as to offer no resistance to relative movement between the lips 48 and 49 and the members 30 and 31.

To prevent any rotation of the lip-carrying end 40 members 39, 39 upon the rotation of the agitator, which is itself connected from its reduced central pulley portion through the belt 52 to the pulley 10 on the motor shaft 8, springs 53, 54, and 55 are provided on the front, the top, and the rear 45 walls of the nozzle 1 at each end thereof. These springs contact the sides of the end members 39, 39 and clearly prevent any appreciable rotation in those members though offering substantially no resistance to vibratory or translatory movement thereof, within certain limits. The presence of these springs 53, 54, and 55 at the ends of the nozzle in contact with the end members 39, 39 removes any stress from the seals 50 and 51, which might otherwise be imposed thereon upon the 55 operation of the cleaner.

In the operation of the suction cleaner, constructed in accordance with this preferred embodiment of the invention, upon the rotation of the cleaner motor the suction-creating fan 9 60 revolves at high speed creating a reduced pressure in the fan chamber 2 which is immediately effective in the nozzle 1, connected to the fan chamber by means of the air passageway 3, resulting in the lifting of the surface covering below the nozzle 1 into contact with transversely extending lips 48 and 49 which define the nozzle mouth. The rotation of the motor shaft 8 is transmitted, through the pulley 10 and belt 52, to agitator 15 which is rotated at high speed upon its bearings 21, 21 carried by the stationary shaft 20 which is itself carried by the end members 28, 28 of the agitator-supporting frame. Upon the rotation of the agitator 15 the cup members 25, 25 carried at the ends thereof, together with 75

their eccentric seats 26, 26, are also rotated resulting in the revolution of the lip-carrying end members 39, 39, which are resiliently positioned relative to the nozzle by the springs 53, 54 and 55, and which enclose by their central seats 40, 40 the eccentrics 26, 26, about the shaft 20 of the agitator. Attention is specifically directed to the fact that the end members 39, 39 do not rotate about the shaft 20 as an axis but instead 10 revolve thereabout. As the lips 48 and 49 are rigidly connected to the end members 39, 39 they receive the identical motion which is imparted thereto and in effect describes small circles and so function to agitate, flex and vibrate the pile 15 of the surface covering with which they contact. As the air drawn into the suction nozzle by the suction-creating fan must enter the nozzle under the lips 48 and 49, they being sealed to members which contact the nozzle walls, it is 20 apparent that the agitation effected by the lips 48 and 49 is at the exact point of cleaning air effectiveness. It is clear, therefore, that in the suction cleaner constructed in accordance with the present embodiment, the surface covering is 25 agitated, in the sense of being beaten, vibrated and brushed by the rigid beating elements of the rotary agitator and by the brush elements thereof, and the pile of the covering is additionally vibrated and flexed by the agitating lips 48 30 and 49.

To remove the agitator 15 from the supporting frame within which it is mounted it is only necessary to pivot the end members 28, 28, together with their cross members 30 and 31, downwardly 35 from the nozzle 1 about their pivot points 29, 29. With the supporting frame pivoted downwardly to the position shown in Figure 1 it is then possible to pivot the upper portions 42, 42 of the end members 39, 39 in a counterclockwise direction 40 relative to the lower portions 41, 41 thereof, it being only necessary to exert an inward force upon each thumb lock spring 45 in order to detach the detent 46 from its seat 47 in the member 41 to make that movement possible. With the 45 portions 42, 42 pivoted from the portions 41, 41 of the end members, it is then only necessary to pivot the locking cam members 32, 32 against the force exerted by the springs 35, 35 in order to 50 permit the ends of the agitator-supporting axle 20 to be removed outwardly from the slots 27, 27 in the end members 28, 28. The replacement of the agitator in the nozzle 1 is simply the reverse operation.

Referring now to Figures 9 to 15 inclusive a second preferred embodiment of the present invention is disclosed, the suction cleaner nozzle being again indicated by the reference character 1. The rotary agitator 57 comprises a hollow cylindrical body 58 having end members 59 and 60 which is provided upon its surface with the rigid elongated beaters 60, 60 and carries below its surface the removable brush elements 61, 61, as in the previous embodiment. Agitator 57 is rotatably and eccentrically mounted upon the stationary supporting shaft 62 by means of the bearings 63, 63 which are seated in seats 64, 64, in each end plate 59. As is clearly seen in Figure 9 the imaginary center axis of the cylindrical body 58 is the center line indicated by the reference character A, while the center line of the shaft 62, and so the bearings 63, 63 as well as the seats 64, 64, is the center line indicated by the reference character B. As in the previous embodiment the agitator 58 is connected by the belt 52 to the shaft of the driving motor. Thread-

ed on to the end of shaft 62 is a stationary end member or thread guard 65 which is concentric with the shaft 62 being of sufficient diameter to enclose the end of the cylindrical agitator body at its greatest radius from the shaft. Secured 5 to each thread guard 65 by means of spaced headed screws 66, 66, of which there are four at each end, is an end plate 67, an insert or filler member 65a being provided therebetween to insure sufficient seating surface for the end plate. 10 Carried by and extending between the end plates 67, 67 at each end of the agitator which are the transversely extending surface-contacting members 68 and 69 which extend entirely across the nozzle mouth parallel to the agitator 57 and 15 spaced therefrom.

The agitator-supporting frame comprises pivoted end plates which are here indicated by the reference character 70, 70 and which are pivoted at the rear of the nozzle upon the pins 71, 71. 20 Between members 70, 70 of the agitator-supporting frame is a front transverse member 72 which lies against and in contact with the front wall of the nozzle 1 and, in the present embodiment, extends downwardly at an angle therefrom to 25 form the front nozzle lip. There is no rear transverse member in the agitator-supporting frame, as in the first embodiment, the rear nozzle lip 73 being rigidly carried by the nozzle 1. As in the first embodiment each end member 70 of 30 the agitator-supporting frame is provided with a slot, here indicated by the reference character 74, and in this slot is positioned a pin 75 which in each instance is locked in place by a cam member 76 under the influence of a pivoting 35 spring 77. The pin 75, in each end of the nozzle is carried by a cup member 78 which encloses and firmly seats a resilient rubber disk 79 which is provided with four spaced seats 80, 80 etc. which are adapted to receive and seat the extended heads of the screws 66, 66, aforescribed. 40

In the operation of the present embodiment of the invention, constructed in accordance with the showings of Figures 9 to 15 inclusive, upon the rotation of agitator 57 the agitator in starting 45 rotates about the center line B, of the shaft 62. As the rotational speed of the agitator increases, however, it tends to rotate about its own imaginary center axis, which is indicated in Figure 9 by the line bearing the reference character A, 50 and accomplishes this end before its normal speed is attained. Upon the agitator rotating about this imaginary axis it is apparent that the shaft 62 will revolve once, upon each rotation of the agitator, about the imaginary center line A in 55 a circle having a radius equal to the distance between the two center lines. This relative movement of the shaft 62 relative to the cleaner nozzle and to the supporting agitator frame is made possible through the resilient mounting of the supporting screws 66, 66 etc. in the resilient bodies 79, 79 at the agitator ends. As the agitator revolves about its own absolute and instantaneous center, that indicated by the axis line bearing the reference character A, the end plates 67, 67, 65 carried rigidly upon the axle 62 receive a translational or rotational motion in that they are revolved about the imaginary axis of rotation of the agitator. This motion of the end plates 67, 70 70 is, of course, effective in the surface-contacting agitating elements 68 and 69, which in the present embodiment are not nozzle lips, but merely positively actuated agitating elements which are adapted to vibrate and flex the pile of the surface covering which they contact. Each agi- 75

tator 68 and 69 positively vibrates the surface covering with which it contacts upon being vibrated by the motion aforescribed.

To remove the agitator from its supporting frame within the nozzle it is only necessary to pivot the end members 70, 70 downwardly from the nozzle, pivot the locking cam members 76, 76 rearwardly to permit the withdrawal of the supporting pins 75, 75 from the slots 74, 74, and 5 the rotary agitator, together with the vibrating agitators 68 and 69 and their supporting end members 67, 67, can be withdrawn as a unit. Thereafter the unit can be disassembled in an obvious manner.

15 Referring now to Figure 16 in particular a further type of agitator, indicated generally by the reference character 80, is shown which is adapted to be embodied in the modification shown in Figures 9 to 14. Agitator 80 comprises an elongated 20 body 81 having a centrally located pulley 82; spaced bristle tufts 83, 83 etc. are carried by the body 81, the latter being rotatably and eccentrically mounted at each end upon a shaft 84 through a bearing 85, the body and the supporting shaft 84 having different center lines. It is apparent that, upon the rotation of agitator 80, as in the last described embodiment, the agitator will, at high speed, rotate about its own 25 imaginary center line resulting in the revolution 30 of the supporting axle thereabout and thereupon resulting in the movement of end members 86, 86 together with the transversely-extending agitators 87, as in the aforescribed embodiment. Spaced supporting means 88, 88 etc. are provided 35 on the end members 86, 86 which are adapted to be seated in the seats 80, 80 of the resilient discs.

I claim:

1. In a suction cleaner, a body including a nozzle, a rotary agitator mounted in said nozzle, 40 a movably mounted transversely extended surface-agitating element in said nozzle, a member at the end of said agitator connected to said element, means mounting said member for movement in all directions in a plane perpendicular 45 to the axis of rotation of said agitator and preventing rotation thereof, said member being also connected to said agitator eccentrically relative to the axis of rotation to be actuated thereby upon rotation of said agitator for the purpose of 50 actuating said element.

2. In a suction cleaner, a rotary surface-beating agitator, means to rotate said agitator, an elongated thin surface-contacting element at the side of said agitator of such thickness that it is 55 adapted to penetrate between adjacent tufts of pile of a surface covering undergoing cleaning, and means to vibrate said element in a direction having a horizontal component.

3. In a suction cleaner, an agitator including 60 rigid beaters, means to actuate said agitator, an elongated thin surface-contacting element at the side of said agitator, and means to vibrate said element, said surface-contacting element forming a nozzle lip for said cleaner.

4. In a suction cleaner, a body, a rotary agitator carried by said body, means to rotate said agitator, an eccentric carried by said agitator, a member carried by and supported on said eccentric for translation relative to the center of rotation of said agitator upon its rotation, means preventing rotation of said member about its own axis, and a surface-contacting element connected to said member at a point spaced from said eccentric and movable therewith.

75 5. In a suction cleaner, a body, a rotary agi-

tator carried by said body, means to rotate said agitator, eccentrics carried by said agitator at the ends thereof, members carried by and supported on said eccentrics, means preventing rotation of said member about their own axes, and a surface-contacting agitating element connected between said members at the side of said agitator.

6. In a suction cleaner, a body, a rotary agitator positioned in said body, means to rotate said agitator, eccentrics mounted at the ends of said agitator and adapted to be rotated therewith, members mounted on the eccentrics, means preventing rotation of said members and permitting limited displacement thereof in all directions in 15 a plane perpendicular to the axis of rotation of said agitator, surface agitating elements connected between said members and means sealing said elements to the surrounding nozzle so that they define the sides of the nozzle mouth and 20 function as nozzle lips.

7. In a suction cleaner, a nozzle, a rotary agitator including an elongated body in said nozzle, bearing means associated with said body eccentrically positioned relative to its axis of rotation and surrounding that axis, members seated on said bearing means, means preventing rotation of said members about their own axes, surface-contacting means extended at the sides of 25 said body and carried by said members, and 30 means to rotate said agitator.

8. In a suction cleaner, a nozzle, a rotary agitator in said nozzle including a body, a shaft eccentrically and rotatably supporting said body, a member rigidly connected to said shaft and 35 movable therewith, a surface-contacting agitating element carried by said member, means supporting said member and said shaft for translation, and means to rotate said body, the mass of 40 said body being such that it rotates about its true center at its normal speed of rotation.

9. In a suction cleaner, a nozzle, a rotary agitator in said nozzle including a body, a shaft eccentrically and rotatably supporting said body, means resiliently supporting said shaft in said 45 nozzle, an elongated thin surface-agitating element connected to said shaft and movable therewith, and means to rotate said body, characterized by the fact that at its normal speed of rotation said body rotates about its center as an 50 axis causing said shaft to move relative thereto.

10. In a suction cleaner, a body including a nozzle, a surface-contacting lip under which cleaning air passes defining one side of the mouth of said nozzle and movable relative thereto, a surface-contacting agitator in said nozzle, and means 55 to actuate said agitator and said lip.

11. In a suction cleaner, a body including a nozzle, a surface-contacting lip under which cleaning air passes defining one side of the mouth 60 of said nozzle and movable relative thereto, a rotary surface-contacting agitator in said nozzle, power-transmission means connected to said agitator, a driving motor, and means connecting said lip to said agitator to vibrate the former 65 upon the rotation of the latter.

12. In a suction cleaner, a body including a nozzle, a rotary agitator including a shaft supporting said agitator at its end, a member at the end of said agitator, a bearing eccentrically 70 mounted on said agitator surrounding said shaft, and supporting said member to impart motion to it upon the rotation of said agitator, resilient means preventing the rotation of said member about its own axis upon the rotation of said agi- 75

tator, a surface-agitating element mounted on said member to move with it, and means to rotate said agitator.

13. In a suction cleaner, a body having a nozzle portion, a rotatable body carried on said first mentioned body at said nozzle portion, means to rotate said rotatable body, an eccentric carried by said rotatable body, a member carried by and supported on said eccentric for translation relative to the axis of rotation of said rotatable body, means preventing rotation of said member about its own axis, and a surface-contacting element carried by said member and movable with it.

14. In a suction cleaner, a body, a rotatable body on said first-mentioned body, a shaft eccentrically and rotatably supporting said rotatable body, a member connected to said shaft and movable therewith, a surface-contacting agitating element carried by said member, means supporting said member and said shaft for translation, the mass of said rotatable body being such that it rotates about its true center at its normal speed of rotation thereby causing said member and element to be vibrated, and means to rotate said rotatable body.

15. A suction cleaner having a nozzle mouth and an air passageway leading therefrom, a fan chamber open to said passageway at a point spaced from said mouth, a driving shaft extended

through said fan chamber into said passageway, a fan on said shaft in said chamber to create a reduced pressure in said passageway and nozzle upon the rotation of said shaft, a rotatable unbalanced mass mounted for rotation and translation at the nozzle mouth, power transmission means connecting said mass to said shaft to cause rotation in the former, and a non-rotatable surface-contacting beater element connected to and translatable with said mass.

16. The construction recited in the preceding claim in which resilient means support said unbalanced mass for translation in the nozzle mouth.

17. A suction cleaner having a nozzle mouth and an air passageway leading therefrom, a fan chamber open to said passageway at a point spaced from said mouth, a driving shaft extended through said fan chamber into said passageway, a fan on said shaft in said chamber to create a reduced pressure in said passageway and nozzle upon the rotation of said shaft, a rotatable member in said nozzle mouth, a surface-contacting element mounted for translation, a translatable member carried eccentrically by said rotatable member and carrying said element, and means preventing rotation of said translatable member.

WILLIAM H. KITTO.
